CLAIM

I claim the ornamental design for side frame for modular furniture, as shown and described.

DESCRIPTION

FIG. 1 is a front view of a side frame for modular furniture; FIG. 2 is a rear view of the side frame of FIG. 1; FIG. 3 is a top view of the side frame of FIG. 1; FIG. 4 is a bottom view of the side frame of FIG. 1; FIG. 5 is a left view of the side frame of FIG. 1; FIG. 6 is a right view of the side frame of FIG. 1; FIG. 7 is a left perspective view of the side frame of FIG. 1; FIG. 8 is a right perspective view of the side frame of FIG. 1; and, FIG. 9 is a perspective view of the side frame of FIG. 1 shown in a state of use.

The broken lines shown in the drawings are for illustrative purposes only and form no part of the claimed design.
